UNITED STATES PATENT OFFICE

HOWARD M. TAYLOR, OF BALTIMORE, MARYLAND

DESIGN FOR A COMBINED ADVERTISING STAND AND MATTRESS SUPPORT

Application filed May 27, 1931. Serial No. 40,014. Term of patent 14 years.

To all whom it may concern:

Be it known that I, HOWARD M. TAYLOR, a citizen of the United States of America, residing at Baltimore city, State of Maryland, have invented a new, original, and ornamental Design for a Combined Advertising Stand and Mattress Support, of which the following is a specification, reference being had to the accompanying drawing, forming part thereof.

In the drawing,

combined advertising stand and mattress support, showing my new design which consists of a stand having means to hold a mattress for display purposes only and which is to remain intact as constituting a part of the entire display; and

I claim:

The ornamental design for a combined advertising stand and mattress support, as shown and described.

HOWARD M. TAYLOR.
